UNITED STATES PATENT OFFICE.

FRANK W. MIX, OF NEW BRITAIN, CONNECTICUT.

LOCK.

SPECIFICATION forming part of Letters Patent No. 404,048, dated May 28, 1889.

Application filed March 31, 1888. Serial No. 269,072. (Model.)

To all whom it may concern:

Be it known that I, FRANK W. MIX, a resident of New Britain, in the county of Hartford and State of Connecticut, have invented 5 certain new and useful Improvements in Locks for Post-Office Lock-Boxes; and I do hereby declare the following to be a full, clear, and exact description of the invention, such as will, enable others skilled in the art to 10 which it appertains to make and use the same.

My invention relates to an improvement in tumbler-locks of a class specially adapted for the securing in closed adjustment of doors on boxes or pigeon-hole receptacles which are 15 arranged in tiers for the safe delivery of mail-matter in post-offices or other similar uses. In order to render locks for this particular use secure and permit an alteration to be effected in its locking mechanism when 20 a key is lost or in the hands of unauthorized parties, a lock has been devised and patented which will allow such a change to be made. In the use of such a lock it is necessary that the works which operate to secure the slide-bolt shall require a positive action of the key 25 to open it or lock it.

It has been found in use that where safety-locks of the type above indicated are applied to the lock-boxes of "post-offices" the requirement of a positive action of the key to lock 30 the door is to a certain extent inconvenient, as parties in the hurry of business frequently withdraw the key after unlocking the door of the box and deposit the same in their pockets. If the door of a lock-box having a safety-lock 35 made as above stated is inadvertently closed by slamming it when the bolt is in locked position, the slide-bolt will be bent or the shock may break the glass front plate of the box; or, if the key is withdrawn while the lock-bolt is retracted, the door will of course 40 be left unlocked.

The object of my present invention is to provide a means to obviate the inconvenience 45 of having to use the key of a positive-action tumbler-lock which is applied to the door of a lock-box post-office delivery, as hereinbefore mentioned, and also avoid the disadvantages which might result from the closure of a 50 door the lock of which has been left in a locked position of its bolt.

With these objects in view my invention

consists in certain features of construction and combination of parts, which will be hereinafter described, and pointed out in the 55 claims.

Referring to the drawings, Figure 1 is a plan view of a lock-casing with its cap-plate removed, as are all the interior works with the exception of the slide-bolt plate and an 60 attached bolt. Fig. 2 is a side elevation in section of the lock-casing with the slide-bolt in place. Fig. 3 is a detached enlarged view of the slide-bolt plate, the latching outer end of an attached slide-bolt being shown in section.

A represents the casing of a lock, preferably cut and stamped into form. This casing is rectangular, with an integral back plate, B, the rim or wall *a* being bent therefrom 70 and joined at the corners to form a casing with a smooth interior surface. The back plate, B, is perforated at several points for the accommodation of studs and other mechanical details of the lock mechanism not 75 necessary to show in this connection, it being specified that the working parts of the lock are of such a form as to secure the slide-bolt in either a locked or unlocked position until moved by a proper key.

Within the casing A the slide-bolt plate C is placed so as to rest upon the back plate, B, the general form of the slide-bolt plate corresponding with that of the casing, and it is of such comparative width that it will slide 85 neatly therein, the plate B being long enough to allow the necessary throw of the same in either direction to lock or unlock a door on which the lock is affixed.

The slide-bolt plate C is adapted to afford 90 support to tumbler mechanism that is employed to control the throw of this bolt-plate, as before stated, which may be varied in form and method of operation; hence it is not shown.

Upon the side edge of the slide-bolt plate B—a proper distance to afford the requisite strength—the slide-bolt D is integrally formed by bending a portion of the material of the plate B at a right angle thereto, the bolt thus 100 produced having sufficient length to permit it to extend through a slot formed near the corner *b* of the casing-wall *a*.

The length of the slide-bolt D is made to

suit the relative position of the lock upon a lock-box door to which it is attached, as the width and formation of the door may arbitrarily control the placing of the lock and consequent length required for the bolt to engage its keeper properly. The form of the door is not material, and as letter lock-boxes are a well-known device it is not deemed necessary to show one in this connection.

10 The outer end of the slide-bolt D, at a point outside the casing, is slotted edgewise a proper depth to afford two parallel walls, c, between which the latch-plate E is located. This plate is triangular in form and pivoted to the ears 15 d, which are formed on the walls c at their top corners.

It may here be specified that the space i, formed between the two parallel walls c on the end of the bolt D, may be produced by a proper tool that is adapted to remove a portion of the material from the solid end of the bolt. A preferred form for the construction of this end of the bolt B is shown in Fig. 1, which consists in the attachment to the side 25 of the bolt proper of an offset jaw, e, which is riveted or otherwise secured thereto, so as to produce a space for the reception between the two pieces of the latch-plate E.

The upper end of the latch-plate is rounded 30 to conform to the shape of the ears d, and a shoulder, f, is produced on the outer edge of the plate E, at the heel of the rounded upper end of this plate, which shoulder is slotted to allow one end of the finger-spring F to be embedded in the latch-plate E, the free end of 35 this spring engaging the terminal wall of the slot or space i, so as to force outwardly the latch-plate and hold it normally so projected.

When the outer edge of the latch-plate E 40 is outwardly projected, as just stated, said edge will be given such an inclination from a perpendicular line as to form a yielding latch, the edge being slightly curved to facilitate its yielding action when it is caused to 45 abut against the edge of the door-frame. From the point h the lower portion of the latch-plate E is rounded to form an arc of a circle, the center of which is the axis of the pivot-support of this plate, so that the vibration 50 of the latch-plate on its pivot will cause its free curved lower edge to have sliding contact with the check bar or step k, against which a projecting toe, m, formed on the inner corner of the latch-plate, is made to abut 55 by the expansive force of the bent finger-spring F, thus restricting the outward movement of the latch-plate by the spring.

It is evident from the foregoing description of the spring attachment, as applied to slide-bolts of locks which are moved positively and held against retraction unless a proper key is used, that slamming shut of a door of a post-office box or other similar receptacle which is furnished with such a lock and also with the yielding latch-plate, hereinbefore described, will cause the latch-plate E to abut against the edge of the door-frame and yield readily and sufficiently to permit said door to be entirely closed and locked without the use of the key.

The construction of the spring-latch E will prevent any tampering with the spring-latch or opening of the door without the proper key, as the coaction of the check-bar k and toe m will convert the latch-plate into a firm abutment, which will not yield to an outward pull of the door until the slide-bolt is withdrawn in a legitimate manner.

Slight changes might be made in the constructive details of this latching device without departing from the spirit of my invention; hence I do not wish to restrict myself to the exact forms herein shown; but,

Having fully described my invention, what I claim as new, and desire to secure by Letters Patent, is—

1. In a lock, the combination, with a sliding bolt, of a latch pivoted to and projecting beyond the outer end of the bolt and wholly supported thereby, substantially as set forth.

2. In a lock, the combination, with a sliding bolt having an open slot formed in its outer end, of a yielding latch pivoted within said slot and located wholly outside the lock-casing, substantially as set forth.

3. In a lock, the combination, with a sliding bolt having a stop formed thereon, of a latch pivoted to and carried by the sliding bolt and arranged to project beyond its outer end, said latch being provided with a projection that engages a stop on the bolt for limiting its outward movement, and a spring for forcing the latch to the limit of its outward movement, substantially as set forth.

In testimony whereof I have signed this specification in the presence of two subscribing witnesses.

FRANK W. MIX.
